UNITED STATES PATENT OFFICE.

WARREN MACPHERSON, OF CAMBRIDGE, MASSACHUSETTS.

FOOTWEAR.

Application filed March 18, 1924. Serial No. 700,139.

This invention relates to a shoe used in playing athletic games such as tennis and basket ball, and having a thick rubber outer sole providing a clinging tread.

5 The invention is particularly applicable to a vulcanized shoe which includes an upper of duck or canvas, and a bottom superstructure which is vulcanized to the upper and to the rubber outer sole.

10 It has been found that the rough surface of crepe rubber constitutes a very desirable clinging tread. The methods employed in making crepe rubber are such that the rubber can be produced only in a sheet of limited thickness, so that an outer sole composed entirely of a piece cut from such sheet would be too thin for use in a sport shoe. Heretofore outer soles with crepe rubber treads have been produced by cementing together 15 several superimposed plies or layers of unvulcanized crepe rubber until the desired thickness is attained, and cementing the layers together, the sole thus formed being subsequently vulcanized. Objections to this 20 method are as follows:

1. The rough surface of the rubber presents a multiplicity of projections and depressions, so that when the layers are assembled, air spaces are liable to occur in 25 the joints formed by the meeting of the layers, there being several joints, each liable to have air spaces. The air thus confined is expanded by heat during vulcanization, so that blisters are often formed.

30 2. The layers do not contact with each other when the air spaces are formed, so that they are liable to be torn apart when the completed sole, incorporated in a shoe, is subjected to the strains incidental to the 35 playing of athletic games.

40 3. Because of the roughness of the inner side face of the sole, said face cannot be attached as firmly to that portion of the shoe to which the outer sole is united in a vulcanized shoe, as would be the case if said face were smooth.

45 4. The edge face of the sole between its inner and tread faces is also rough, and presents an unsightly appearance, said edge face being necessarily of considerable width and thickness.

50 I obviate these objections by the improved construction of the outer sole hereinafter described and claimed.

Of the accompanying drawings forming 55 a part of this specification,—

Figure 1 is a side view of a vulcanized shoe having an outer sole embodying the invention.

Figure 2 is a bottom view of the rubber 60 outer sole shown by Figure 1, the toe portion being broken away.

Figure 3 is a section on line 3—3 of Figure 2.

Figure 3^a is a fragmentary sectional view, 65 showing portions of the two layers forming the outer sole, before said layers are assembled.

Figure 4 is a section on line 4—4 of Figure 1.

Figure 5 shows in section portions of the upper and the bottom superstructure of a vulcanized shoe, assembled on a last, and a portion of the outer sole in position to be applied to the superstructure, the vulcanizable parts being supposed to be unvulcanized.

70 The same reference characters indicate the same parts in all of the figures.

In the drawings *a* designates the canvas 80 upper of a vulcanized shoe. With the upper is associated an inner sole *b*, over which the margin *a'* of the upper is drawn, and a binder *c*, placed upon the margin *a'* and the portion of the inner sole surrounded by said 85 margin. The binder is prepared for vulcanization, and is composed of fibrous material and rubber cement, or other form of unvulcanized rubber. The fibrous material may be either in the form of woven fabric, 90 such as duck or canvas, or of fibers which are not interwoven.

95 The parts above described are assembled on a last *d*, as indicated by Figure 5. The assemblage may include a foxing *e* of unvulcanized rubber, applied as shown to cover portions of the upper and the binder. The binder *c* constitutes a vulcanizable element of a bottom superstructure, to which the rubber outer sole hereinafter described is 100 vulcanized.

105 In carrying out my invention, when the same is embodied in a vulcanized shoe, I complete the bottom of the shoe by applying to said superstructure a two-layer outer sole, composed of a relatively thick body layer 12 of rubber soling, distinguished as herein-after stated, and having substantially smooth

surfaces, and a thinner facing layer or veneer 13 of crepe rubber having the usual rough surfaces. Said layers are prepared for vulcanization, assembled while unvulcanized, and united to each other by a vulcanizing operation which unites the body layer 12 to the vulcanizable element of the bottom superstructure, said element in this instance, including the binder *e* and the foxing *e*, although if the foxing is not employed, the vulcanizable element will include only the binder.

In stating that the body layer 12 is composed of rubber soling, I mean rubber compounded for vulcanization in the manufacture of relatively thick elastic soles for sport shoes, and formed into a layer having substantially smooth surfaces and of uniform density, so that there are no air spaces between the external surfaces.

The preferred rubber soling is composed of pure or nearly pure gum rubber, compounded for vulcanization and run through a soling calender in the form of a sheet, having approximately two-thirds of the thickness of the completed sole. A thinner sheet of crepe rubber, compounded for vulcanization and produced in the usual manner, and having the usual thickness of crepe rubber, is rolled and pressed while unvulcanized on to the sheet of rubber soling, thus bringing the two-part sheet up to the required thickness of the outer sole, which is died out of the sheet by the usual means. The sheet of rubber soling has substantially smooth surfaces and is of uniform density without air spaces or blow holes.

In the formed outer sole, the rough top face of the facing layer, is conformed by pressure to the smooth bottom face of the body layer, so that a joint is formed which is free from air spaces.

The smooth inner face of the body layer so contacts with the superstructure of the bottom that a joint is formed which is also free from air spaces.

The edge face of the two-part sole is formed by the instrumentalities which cut the sole from the two-part sheet. That portion or zone of the edge face formed on the body layer, constituting the major portion of the edge face of the completed sole, presents a smooth finished appearance. The tread face of the sole and the narrow zone of the edge face formed on the facing layer, present the usual appearance and have the usual roughness of crepe rubber.

I prefer to thicken the heel portion of the body layer 12, and thus provide the sole with a spring heel having an inclined breast 15. This thickening may be imparted by the calender rolls which form the body sheet.

My improvement above described obviates the objections above mentioned, by pre-

venting blistering of the outer sole in the vulcanizer, preventing liability of separation of the tread portion from the portion above it, causing perfect adhesion of the inner surface of the sole to the superstructure, and providing the major portion of the outer sole edge with a smooth slightly face.

The improved outer sole, therefore, has all of the advantages and none of the disadvantages of a crepe rubber sole as heretofore prepared, and is less expensive than the latter.

Although I have particularly described my invention in connection with a vulcanized shoe, it is to be understood that I am not limited to this particular type of shoe, excepting as hereinafter specified in one of the appended claims.

I claim:

1. A two-layer rubber outer sole composed of a relatively thick body layer of rubber soling, free from air spaces and having smooth surfaces, and a thinner tread layer of rough surfaced crepe rubber pressed against the body layer, to conform its top surface to the bottom surface of the body layer, and thereby form a joint which is free from air spaces, said layers being united by vulcanization, the sole being characterized by operative thickness, a smooth surfaced top face adapted to conform and be united by vulcanization to the bottom face of a superstructure, without forming air spaces between said faces, a smooth surface marginal face imparting a desirable finish to the major portion of the sole edge, and a clinging rough-surfaced tread face, there being an absence of air spaces throughout the entire mass of the sole.

2. A vulcanized shoe comprising a bottom including a superstructure vulcanized to the upper; and a two-layer outer sole composed of a relatively thick body layer of rubber soling, free from air spaces and having smooth surfaces, and a thinner tread layer of rough-surfaced crepe rubber pressed against the body layer to conform its top surface to the bottom surface of the body layer and thereby form a joint which is free from air spaces, said layers being united by vulcanization, the top surface of the body layer being conformed and united by vulcanization to the bottom face of the superstructure, without forming air spaces between said faces, the smooth marginal face of the body layer imparting a desirable finish to the major portion of the sole edge, the bottom face of the tread layer constituting a clinging rough-surfaced tread face, and the outer sole being free from air spaces throughout its entire mass.

In testimony whereof I have signed my signature.

WARREN BACHMAN, JR.
